UNITED STATES PATENT OFFICE

2,279,768

MANUFACTURE OF SLIDE FASTENERS

Frederick Ulrich, Bayonne, N. J., assignor to
 Conmar Products Corporation, Bayonne, N. J.,
 a corporation of New Jersey

Application December 20, 1940, Serial No. 370,947

15 Claims. (Cl. 164—60)

This invention relates to the manufacture of slide fasteners, and more particularly to the manufacture of a wire comprising a series of embryo slide fastener elements.

The primary object of my invention is to generally improve the manufacture of slide fasteners.

In my Patent No. 2,221,740, I disclose a wire having closely spaced interlocking means at the top and bottom surfaces and closely spaced notches or serrations at the side edges, the serrations corresponding to the outer ends of spread jaws. The spacing is preferably only a fraction of the length of the elements, so that the strip provides metal for a series of slide fastener elements with the embryo head of one element nested within and filling the space between the embryo spread jaws of the next embryo element.

This wire is preferably formed by rolling a smooth or uniform wire between small-diameter die rolls carried in massive shafts and bearings such that adequate pressure may be exerted on the wire to fully shape the same in a single passage through the rolls. With both rolls oppositely recessed, a thin fin or web of metal remains in the notches, because it is difficult to completely control the flow of the metal. A soft metal is not satisfactory for a long-wearing slide fastener, and with a satisfactory hard metal, a residue or fin remains in the notches. This fin may be cut away in the machine which attaches the elements to a tape, all as disclosed in my co-pending application Serial No. 264,550, filed March 28, 1939.

However, there is some inconvenience attendant upon cutting the fin at the attaching machine, and one object of the present invention is to overcome this difficulty.

The tiny triangular pieces of web which must be cut from the side edges of the wire are so small that they tend to clog the cutting punch of the attaching machine unless they are effectively cleared away by means of an air blast or the like. Consequently compressed air must be piped to each of the scoop machines. In accordance with the present invention, the fin is trimmed or cut away by a cutting roll through which the wire is passed. It is desirable to use an air blast even when using a rotary cutter as here disclosed, but the rotary cutting operation is very fast, and a single rotary machine for trimming the wire will suffice for the treatment of enough wire for a battery of attaching machines. The problem of piping and supplying compressed air for the rotary machine is therefore a minor matter com-

pared to the corresponding problem when the fin is trimmed in the attaching machine.

Further and more specific objects of the invention are to provide means to positively feed the wire through the cutting roll while at the same time affording self-adjustment of the side-ward position of the wire relative to the cutting roll; to provide means for cleaning the cutting roll; and to provide means for additionally vibrating and cleaning the trimmed wire, all with a view to insuring removal of the tiny pieces of cut fin from the wire before it is reeled for delivery to the attaching machines.

To the accomplishment of the foregoing and such other objects as will hereinafter appear, my invention consists in the cutting rolls and associated mechanism and their relation one to the other, as hereinafter are more specifically described in the specification and sought to be defined in the claims. The specification is accompanied by drawings, in which:

Fig. 1 is a front elevation of a rolling machine provided with the cutting rolls of the present invention;

Fig. 2 is a plan view of part of the apparatus localized at the rolls and drawn to enlarged scale;

Fig. 3 is a section taken in elevation in the plane of the line 3—3 of Fig. 2;

Fig. 4 is a front elevation of a cutting roll and mating roll with the wire sectioned therebetween;

Fig. 5 is a plan view of a piece of wire partially run through the rolls;

Fig. 6 is a section taken in the plane of the line 6—6 of Fig. 4, but drawn to enlarged scale;

Fig. 7 is a transverse section taken in the plane of the line 7—7 of Fig. 6;

Fig. 8 is a fragmentary section explanatory of the operation of the invention, and is taken in the plane indicated at 8—8 in Fig. 5; and

Figs. 9, 10, and 11 are similar views, but showing successive stages in the operation of the cutting roll.

Referring to the drawings, and more particularly to Fig. 5, the slide fastener wire is preferably made by rolling and deforming a uniform wire of round or rectangular section to provide a series of interlocking projections 12 on one side, in this case the upper side, and a series of recesses directly therebeneath on the lower side. These recesses are not shown in Fig. 5, but are indicated in broken lines at 14 in Fig. 6. The side edges of the wire are notched or serrated, as is indicated at 16 in Figs. 5 and 6, but these serrations are marred by a thin web or fin of metal

18. The general purpose of the present invention is to trim or cut away the small triangular pieces of web or fin 18, thus leaving the wire in the cleanly notched or serrated condition shown in the left-hand part of Fig. 5.

Referring now to Fig. 1, the trimming operation is performed by a cutting roll, in this case the upper roll 20, the wire being supported and preferably also fed by means of a mating roll 22. These rolls may, if desired, be so designed and dimensioned as to be received in the shafts of a rolling machine such as that disclosed in Wintritz Patent No. 2,201,068, issued May 14, 1940, although it is not necessary in the present case to use a machine of the heavy construction there disclosed, because the present cutting operation is a light-duty operation compared to the rolling operation for which the aforesaid machine was designed. Specifically, the roll 20 is received in the end of a shaft 24 carried in a bearing 26, said shaft carrying a gear 28 driven by means of a pinion 30 through an idler 32. The roll 22 is carried in the end of a shaft 34 carried in a bearing 36, said shaft 34 carrying a gear 38 meshing with a pinion 40. The pinions 30 and 40 are both carried on a countershaft 42 having a pulley 44 driven by belts 46 running downwardly to a drive motor, not shown in the drawings. Thus the rolls 20 and 22 are rotated synchronously and in opposite directions, as they should be.

Referring now to Fig. 4, the cutting roll 20 comprises an operating portion formed integrally with a tapered shank 50 which is received in the shaft 24 previously referred to. The working portion is deeply grooved at 52, and the resulting opposed face walls of the groove are radially serrated, as is indicated at 54. The spacing between the serrated faces corresponds to the width of the fastener wire. In practical effect, the cutting roll may be considered as comprising two cutting rolls arranged coaxially and bearing against opposite sides of the wire. Each of these cutting rolls has a side face provided with radial serrations. The specific roll here disclosed, however, has been formed out of a single blank of metal, and it is therefore convenient to refer to the complete unit as a cutting roll, although it will be understood that this terminology is not intended to exclude the use of two separate cutting rolls assembled properly for the intended purpose.

To facilitate the formation of the teeth or serrations 54, the groove 52 is preferably undercut or T-shaped, thus forming a space 56 (Figs. 6 and 7) at which the teeth 54 terminate.

Referring now to Fig. 6, the teeth 54 of the rear roll are shown, but the teeth of the nearer roll are omitted. However, the wire and the pieces of web cut therefrom are shown in elevation, and it will be seen how the web is partially sheared away at 58 and is wholly cut away at 60. This cutting action is more clearly shown in Figs. 8, 9, 10, and 11, which illustrate successive stages of the fin-cutting operation. In Fig. 8 the tooth 62 has just begun to bear against the fin 64; in Fig. 9 the leading edge of fin 64 has been cut through; in Fig. 10 the trailing edge of fin 64 is under pressure; and in Fig. 11 the piece of fin is completely sheared from the wire. At the same time the next tooth 66 is about to begin its shearing action on the next fin 68.

Thus the pressure exerted by the teeth is in a radial direction toward the support roll 22, and the triangular bits of fin are sheared transverse-

ly of the wire. This shearing action is possible because the fin is elevated above the bottom of the wire, thus providing a space beneath the fin into which the fin may be forced by the teeth 5 of roll 20. If the fin were located at one face of the wire, it would then be necessary, with the particular rolls here shown, to dispose that face of the wire uppermost, so as to provide the desired space beneath the fin.

As so far described, the lower roll may be a smooth roll, the wire being moved by the upper roll alone, but I find it advantageous and preferable to positively drive the wire by means of the lower roll. For this purpose the lower roll is provided with a series of projections indicated at 70. (If the wire were inverted the roll 22 would be provided with recesses instead of projections.) As will be seen in Fig. 6, the projections 70 are dimensioned to be received in the recesses 14 and to substantially fill the same in order to positively control the wire. However, when looking in a plane transverse to the wire, the tooth or projection 70 is preferably made substantially narrower than the recess 14, as is best shown in Fig. 7. This permits a certain amount of self-adjustable sideward movement of the wire so that it will at all times best fit the cutting rolls. In other words, because the thin fins 64 are readily sheared, whereas the full-thickness metal constitutes a much greater resistance, the wire tends to and does locate itself properly between the two sets of teeth or serrations of the cutting roll.

Referring now to Fig. 3, the fin or scrap for the most part remains on the lower roll 22, and is collected by a scrap discharge pipe or chute 72. The upper end of pipe 72 is cut away so as to rest closely adjacent the surface of roll 22. An air-blast nozzle 74 is preferably disposed in the end of pipe 72, and the resulting discharge of compressed air helps blow the scrap off the roll 22, and also creates a suction within pipe 72 which additionally tends to draw the scrap away from the rolls. Nozzle 74 is formed at the end of a pipe 76 which in turn is connected to a suitable source of compressed air.

The cutting roll may be provided with means to wipe the same free of any stray pieces of fin or scrap adhering thereto. For this purpose, a 50 spring wiper blade 78 is mounted with its end touching the roll 20, thus keeping the peripheral face of the same in clean condition as it rotates toward the wire approaching the roll. In Figs. 2 and 3, the wire moves from right to left and the roll 20 turns clockwise, as viewed in Fig. 3.

In order to guard against the possibility of cut fin or scrap clinging to the trimmed wire 80 which has passed through the rolls, additional 60 means may be provided to remove any such residual scrap. The means here disclosed may be considered to be a vibrating means for vibrating the wire, or may be considered to be a means for physically wiping the serrated edges. The operation is probably a combination of both. Specifically, I provide spring fingers 82 on opposite sides of the wire, the ends of which bear against the serrated edges of the wire. It will be evident that the spring fingers tend to move 70 into and out of the successive serrations and so to clean the same. At the same time, because the tips of the spring fingers are preferably displaced slightly from one another, the wire 80 tends to vibrate as it passes through the spring 75 fingers, thus further tending to clean the wire.

If desired, the wire may be guided to the spring fingers 82 by means of a pair of guide rollers 84 and 86 disposed beneath and above the wire.

The wire approaching the trimming rolls 20 and 22 is preferably guided, as by means of a guide finger 88 which is suitably channeled at 90 to receive the wire. The forward end of the guide finger is cut away and shaped to fit into the groove of cutting roll 20, as is indicated at 92 (Fig. 3), and thus acts as a stripper to guard against any possibility of the wire being drawn upwardly by the teeth or serrations 54 of the cutting roll 20.

The guide and stripper 88, 92 have been omitted in Figs. 4, 6, and 7 in order to more clearly show other parts of the apparatus.

It is believed that the construction and operation of my improved apparatus for trimming fin from slide fastener wire, as well as the many advantages thereof, will be apparent from the foregoing detailed description thereof. It will also be apparent that while I have shown and described my invention in a preferred form, changes and modifications may be made in the structure disclosed, without departing from the spirit of the invention as sought to be defined in the following claims. In the claims the reference to a cutting roll having a deep groove is intended to include the equivalent use of two coaxial rolls with a space therebetween, the space corresponding to the deep groove. Moreover, the reference to the support roll having projections adapted to be received in the recesses of the wire is not intended to exclude the equivalent reversed structure in which the support roll has recesses adapted to receive the projections of the wire. It is possible to drive the support roll only, or if the support roll is smooth, to drive the cutting roll only, but I prefer to drive both rolls synchronously, as described.

I claim:

1. Rotary apparatus for cutting away or trimming fin from the notched side edges of a slide fastener wire, said fin being thin relative to the wire, and located intermediate the top and bottom of the wire, said apparatus comprising first and second rolls with means to guide the wire therebetween, the first roll having opposed face walls with radially extending serrations for bearing radially against the fin, and the other roll being devoid of radial serrations and acting to hold the wire between the rolls for fin shearing action of the serrated roll.

2. Rotary apparatus for cutting away or trimming fin from the notched side edges of a slide fastener wire, said fin being thin relative to the wire, and located intermediate the top and bottom of the wire, said apparatus comprising a cutting roll and a support roll, the cutting roll having a deep groove the opposed face walls of which have radially extending serrations for bearing radially against and shearing the fin transversely of the wire toward the support roll, and the support roll being devoid of radial serrations and acting as means for supporting the wire against the shearing action of the serrated cutting roll.

3. Rotary apparatus for cutting away or trimming fin from the notched side edges of a slide fastener wire, said fin being thin relative to the wire, and located intermediate the top and bottom of the wire, said apparatus comprising a cutting roll and a support roll, the cutting roll having a deep groove the opposed face walls of

which have radially extending serrations for bearing radially against and shearing the fin transversely of the wire toward the support roll, the support roll being devoid of radial serrations and acting as means for supporting the wire against the shearing action of the cutting roll, and means to synchronously rotate said rolls in opposite directions.

4. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, whereby the wire is positively fed by the support roll, and means to synchronously rotate said rolls in opposite directions.

5. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, whereby the wire is positively fed by the support roll, said projections being large enough in the direction of feed of the wire to control the feed, but being much smaller than the recesses in a direction transverse of the wire in order to permit the wire to self-adjustably locate itself relative to the serrations of the cutting roll, and means to synchronously rotate said rolls in opposite directions.

6. Rotary apparatus for cutting away or trimming fin from the notched side edges of a slide fastener wire, said fin being thin relative to the wire, and located intermediate the top and bottom of the wire, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, and means for rubbing against and thereby cleaning said wire of any cut scrap or fin tending to cling thereto.

7. Rotary apparatus for trimming fin from the notched side edges of a slide fastener wire, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, and vibrator means following said rolls for vibrating the trimmed wire in order to dislodge any cut scrap or fin tending to cling thereto.

8. Rotary apparatus for cutting away or trimming fin from the notched side edges of a slide

fastener wire, said fin being thin relative to the wire, and located intermediate the top and bottom of the wire, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, and wiper means formed at one edge of a scrap discharge tube to wipe any cut scrap or fin from the cutting roll.

9. Rotary apparatus for trimming fin from the notched side edges of a slide fastener wire, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, a scrap or waste discharge tube disposed immediately adjacent one of the rolls, and an air-blast tube having a nozzle directed into said waste tube.

10. Rotary apparatus for trimming fin from the notched side edges of a slide fastener wire, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, a scrap or waste discharge tube disposed immediately adjacent one of the rolls, an air-blast tube having a nozzle directed into said waste tube, wiper means to wipe cut scrap or fin from the cutting roll, and spring fingers following said rolls for bearing against the trimmed wire in order to dislodge any residuary cut scrap or fin tending to cling thereto.

11. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, means to rotate said support roll, and vibrator means for bearing against and vibrating the trimmed wire in order to dislodge any cut scrap or fin tending to cling thereto.

12. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means

for supporting the wire against the shearing action of the cutting roll, said support roll additionally having projections adapted to be received in the recesses of the wire, means to rotate said support roll, and wiper means to wipe scrap or fin from the cutting roll.

13. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, means to rotate said support roll, a scrap or waste discharge tube disposed immediately adjacent one of the rolls, and an air-blast tube having a nozzle directed into said waste tube.

14. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, means to rotate said support roll, a scrap or waste discharge tube disposed immediately adjacent one of the rolls, an air-blast tube having a nozzle directed into said waste tube, and means for rubbing against and thereby cleaning the trimmed serrations of the wire in order to dislodge any cut scrap or fin tending to cling thereto.

15. Rotary apparatus for trimming fin from the notched side edges of a slide fastener wire having recesses along one face, said apparatus comprising a cutting roll and a support roll, the cutting roll having a deep groove the opposed face walls of which have radially extending serrations for bearing radially against and shearing the fin transversely of the wire toward the support roll, the support roll acting as means for supporting the wire against the shearing action of the cutting roll, said support roll additionally having projections adapted to be received in the recesses of the wire, said projections being large enough in the direction of feed of the wire to control the feed, but being much smaller than the recesses in a direction transverse of the wire in order to permit the wire to self-adjustably locate itself relative to the serrations of the cutting roll, means to rotate said support roll, a scrap or waste discharge tube disposed immediately adjacent one of the rolls, an air-blast tube having a nozzle directed into said waste tube, wiper means to wipe scrap or fin from the cutting roll, and vibrator means for vibrating the trimmed wire in order to dislodge any cut scrap or fin tending to cling thereto.

FREDERICK ULRICH.
